MARTIN RODERICK O'SHAUGHNESSY, OF COBALT, ONTARIO, CANADA.

STAMP-MILL OR THE LIKE.

1,265,948.

Specification of Letters Patent. Patented May 14, 1918.

Application filed August 16, 1915. Serial No. 45,835.

To all whom it may concern:

Be it known that I, MARTIN R. O'SHAUGHNESSY, a subject of the King of Great Britain, and resident of Cobalt, in the Province 5 of Ontario, Dominion of Canada, having invented certain new and useful Improvements in Stamp-Mills or the like, do hereby declare that the following is a full, clear, and exact description of the same.

- 10 The invention relates to improvements in stamp mills or the like, as described in the present specification, and illustrated in the accompanying drawings that form part of the same.
- 15 The invention consists essentially of the improved construction particularly described and set forth in the following specification and accompanying drawings forming part of the same.
- 20 The objects of the invention are to devise a stamp mill of simple and durable construction which shall have increased efficiency and output over these already in general use and co-incidently lengthen the life of the 25 stamps, shoes and screens, and further maintain the several parts, especially the screen in a clean operative condition.

In the drawings:—

Figure 1 is a perspective view of the mortar having portions thereof broken away.

Fig. 2 is a cross sectional view through the mortar as shown in Fig. 1.

Fig. 3 is a perspective detail view of the mortar chuck.

Fig. 4 is a perspective detail view of the bearing bracket of the reservoir partly broken away.

Like numerals of reference indicate corresponding parts in each figure.

Referring to the drawings, 1 is a stamp mill mortar formed in substantially rectangular shape, and having the dies 2 arranged at intervals therealong at the bottom thereof, and the stamps 3 arranged with the shoe 45 120 attached thereabove, to drop intermittently on the dies.

The mortar box 1 has the opening 4 along the front thereof and in which is fitted the screen 5, which is customarily set at a slight 50 angle outward at the top. The above parts are in general common to stamp mill equip-

ment and construction and in the operation of the mill, crushed ore is fed in the required quantities to the stamps through a suitable opening at the back of the mortar, in such manner that the ore falls on the crushing 55 surface of the dies and is reduced thereon by the constant raising and dropping of the operating stamps. To assist the pulverized mass from the mortar through the screen 5, 60 water or mill solution is supplied with the ore, in sufficient volume to wash out through screen 5, the ore sufficiently reduced to pass said screen openings or orifices, the discharged slime, sand and solution, etc., drops 65 from screen to a receiving launder and is thus conveyed from mortar.

Under ordinary conditions the mill solution consisting of water, cyanid or the like, supplied for the double purpose of washing 70 and assisting in the expulsion of the pulverized mass from the mortar will be an effective agent while screen and mortar clearance is maintained, conditions that will depend on free screen, uniform thin feed of 75 ore to crushing surface of dies and ample volume of mill solution to wash and convey pulverized mass from the mortar. One of the principal difficulties in mill practice is the gradual choking of the screen 5 with foreign solids that are driven against the screen by the action of the operating stamps. In this clogging or choking the effective discharge area of the screen is gradually reduced at its most effective discharge points, 80 85 namely points on the screen surface where the direct wash of the operating stamps is directed. The closing of the screen at these points on screen surface immediately affects the general internal operating conditions 90 causing excessive sliming of the ore at the expense of capacity, and also interferes with the proper clearance of the crushing surface of the dies due in a great measure to excess slimed pulp retained behind screen, bringing into practice a condition of operating mortar whereby the important washing influence of the mill solution is practically lost on the surface of the dies, resulting in dry crushing on the surface of the dies, which 95 100 if continued, even for a short period converts the crushing surface of the dies into

irregular or very uneven surfaces, a very undesirable condition where the life of the wearing parts and the capacity of the stamps are valued. In this arrangement of 5 stamp mill there is of course a maximum output, which in practice has been fairly determined and brought to a standard throughout the various mills in use. It is to greatly increase the tonnage capacity and 10 improve the operating conditions that this invention has to do. I have determined that it is a decided advantage to intermittently change the volume of mill solution supplied to mortar for the double purpose of washing and conveying the reduced ore from the 15 stamps; that is, at one brief period reducing the volume of solution supplied to probably fifty per cent. the required volume so that the ore being reduced under the stamps 20 approaches a thickened or pasty like product during the short solution period, the reduced volume of solution present gives the dropping stamps a more effective chance to reduce the ore, immediately following the 25 short solution period to flood the interior of mortar to any desired height on screen found, best suited for character of ore being reduced by the stamps. The flooding of the interior of the mortar sets up through the 30 action of the stamps active energetic washing influences that readily expels the sufficiently reduced ore from the mortar through the screen, and the mill solution controlling devices as hereinafter described keep the 35 clearance of the screen assured through lengthy operating periods, and in so doing materially assist in maintaining the proper and efficient clearance of the crushing surface of the dies, an all important condition 40 whereby satisfactory operating conditions are valued.

The mortar, as also the spigot trough 6 is supplied with a mill solution to a height as shown in the drawings, that is, slightly over 45 the dies and bottom of the screen, so that the reduced ore is washed about with the splash of the dies and worked through the screen into the spigot trough; the regular dropping of the stamps one after the other along the 50 mortar, setting up a continuous hammering on the dies, so that the agitation of the solution about the dies is constant to a normal degree, and the flow of the same in the spigot trough normal and at a practically 55 normal level.

Again with ordinary practice, the screen is only partially used, the portion used becoming more or less clogged with the constant clinging of reduced matter in its passage therethrough, and in order to increase the efficiency of the screen to take care of the increased output of the stamps I arrange for the flooding of the screen intermittently by sending a wave through the screen, or by

intermittently flushing the said screen on 65 either the inside or the outside in any desired manner, though preferably by the simple arrangement and construction of parts as hereinbefore described.

On the front of the mortar and immediately above the spigot box the flood trough 8 is arranged, said trough having the bottom 9 thereof slanted inwardly to the mortar and terminating on a line there-along approximately two-thirds of the height of the 75 screen 5. The flood trough 8 is secured to the mortar by suitable angle pieces 10 clamped to the bearings brackets 11, by the clamping fingers 12.

13 is a false bottom extending along the 80 flood trough 8 and inclined upwardly and extending along the mortar box immediately above the screen and terminating on a line adjacent to the front of the box above the said false bottom, and having the flap 85 damper 14 hingedly secured along the upper edge thereof whereby said damper may be tilted in relation to the bottom 9 to regulate the extent of the opening between said bottom 9 and the false bottom 13.

The mortar 1 along the front thereof and immediately above the false bottom 13 of the flood trough has the inlet openings 15 through which the stamps are supplied with 95 solution as hereinafter described.

Other forms of intermittent feeding devices may be utilized for regularly supplying an extra quantity of solution to the stamps, and the form shown in the accompanying drawings is only illustrative of a 100 simple device and comprises a reservoir trough 16 extending along the flood trough and having the end trunnions 17 journaled in the bearings 18 of the bearing brackets 11 hereinbefore referred to. Said reservoir 105 trough has an open top and is substantially circular in cross section around the bottom, but one of the longitudinal walls of the trough is formed straight as shown at 19 whereby when the trough is filled to a certain height with solution the contents thereof will over balance the trough and cause it to tilt and discharge the contents thereof, due to the over balance, as is well known in devices of this kind.

Solution is supplied to the flood trough from the feed pipe 20, said pipe however, preferably being branched into the pipe 21 extending over the reservoir trough, the passage of which is controlled by the valve 120 22. A pipe 23 extends along the flood trough immediately above the inlet 15 of the mortar, and is provided with a valve 24; and a pipe 25 extends along the flood trough immediately above the damper 14, which controls the opening between the false and the real bottom of the trough, the pipe 25 being 125 provided with a valve 26.

In the operation of the stamp mill the stamps are dropped upon the dies in a regular manner, and the valve 22 supplied solution through the pipe 21 to the reservoir trough 16, said trough having a suitable number of orifices 27 in the bottom thereof whereby the solution will immediately flow into the false bottom 13 and through the inlet orifice 15 into the mortar about the 5 stamps, said solution flowing in a sufficient quantity to moisten the ore being reduced to bring the same to a pasty condition, but not being sufficient to wash away the finer particles.

10 15 The reducing of the ore under such conditions is remarkably thorough, though it would be entirely impracticable to allow such conditions to continue uninterrupted.

The reduced ore must have sufficient solution to carry it away and this is automatically supplied, as the reservoir trough fills, due to the solution flowing thereunto faster than it is discharged through the outlets 27, so that when the trough tilts, a 20 25 wave of solution flows down the false bottom 13 of the flood trough, through the inlet openings 15 into the mortar and washes away the thoroughly reduced ore.

Coincidentally, the flood or wave of solution from the reservoir trough partly 30 35 passes down the bottom 9 of the flood trough, through the opening regulated by the damper 14 of the false bottom, and this solution passing down the bottom 9, dashes against and through the screen of the mortar from the outside thereof, washing the same and assisting in the agitation of the water within the mortar.

On the continued operation of the stamps, 40 an outward wave of solution occurs and passes through the screen and thoroughly flushes the mortar and carries off all the ore which has been thoroughly reduced into the spigot trough from which it readily passes 45 through the overflow discharge pipe 27.

To aid the flushing of the mortar I place a chuck or ledge strip 29 along the mortar immediately in front of the shoes 2, and this chuck is beveled upwardly from the 50 front of the shoes to the screen opening 5. This chuck 29 is bolted to the front of the mortar by suitable bolts 30 extending outwardly from the chuck through the slots 31 in the front of the mortar, whereby the 55 height of the chuck may be adjusted.

This chuck directs the liquid or solution within the mortar against the screen, and thereby assists in the quick and uninterrupted discharge of the solution from the 60 said mortar.

The general arrangement of the several parts of the invention as hereinbefore described renders the complete mill most efficient, and particularly the intermediate

flooding of the mortar box 1 effectively 65 washes the thoroughly disintegrated solids from the mass being reduced in the stamps, and further effectively expels such disintegrated particles, and the solids after they have, through the action of the stamps 70 reached a state of reduction to permit their passage from the interior of the mortar through the battery screen.

In the above manner excessive sliming of the material in reduction by the stamps is 75 avoided.

As many changes could be made in the above construction, and many apparently widely different embodiments of my invention within the scope of the claims, constructed without departing from the spirit or scope thereof, it is intended that all matter contained in the above specification and accompanying drawings be interpreted as 80 85 illustrative, and not in a limiting sense.

What I claim as my invention is:—

1. In combination, a receptacle with a side screen, a stationary flood trough adjacent to said receptacle and leading to said screen, and a tilting trough adapted to discharge in said flood trough, said flood trough having a pivoted false bottom adapted to discharge material therefrom into 90 said receptacle above said screen.

2. In combination, a receptacle with a 95 side screen, a stationary flood trough adjacent to said receptacle and leading to said screen, and a tilting trough curvilinear in cross section at the bottom and one of the longitudinal walls, the other longitudinal 100 walls being formed straight whereby when the tilting trough is filled, it will overbalance and discharge in said flood trough, said flood trough having a pivoted false bottom adapted to discharge material there- 105 into said receptacle above said screen.

3. In combination, a receptacle with a side screen, a stationary flood trough adjacent to said receptacle and leading to said screen, and a tilting trough in the said 110 flood trough adapted to be automatically tilted under gravity and intermittently fill the flood trough, and means located adjacent to the bottom of the flood trough whereby the material from the trough is discharged into the receptacle above said screen and through said screen.

4. A stamp mill comprising a mortar box, stamps operatively arranged in said mortar box, a discharge screen arranged in a suitable opening in said mortar box, a flood trough arranged along the exterior of said mortar box, a dividing plate arranged in said flood trough, means of communication from one side of said dividing plate to the 120 interior of said mortar box and means of communication from the other side of said dividing plate to the exterior of said screen, 125

and means for intermittently supplying a liquid to said trough on both sides of said dividing plate.

5. A stamp mill comprising a mortar box, 5 stamps operatively arranged in said mortar box, a discharge screen arranged in a suitable opening in said mortar box, a flood trough arranged along the exterior of said mortar box, a dividing plate arranged in 10 said flood trough, means of communication from the other side of said dividing plate to the exterior of said screen, means for continuously supplying a liquid to said trough on the side of said dividing plate communicating with the interior of said mortar box and means for intermittently flooding said flood trough on both sides of said dividing plate.

6. A stamp mill comprising a mortar box, 20 stamps operatively arranged in said mortar box, a discharge screen arranged in a suitable opening in said mortar box, a flood trough arranged along said mortar box on the exterior thereof and having the bottom 25 thereof inclined downwardly and terminating intermediate the height of the screen opening in said mortar box and a false bottom extending part way across said flood trough and inclining downwardly toward 30 said mortar box above said screen and adjustable toward the bottom of said flood trough, means for connecting said flood trough above the false bottom thereof with the interior of said mortar box, means for 35 supplying said flood trough with a regular quantity of liquid and means for intermittently supplying said flood trough with an additional quantity of liquid.

7. A stamp mill comprising a mortar box 40 having a battery screen opening extending along one side thereof and a plurality of mill solution openings therethrough above said screen opening, a battery screen arranged in said screen opening, stamps operatively arranged in said mortar box, a flood trough secured along said mortar box on the outside thereof and having the bottom inclined downwardly and terminating along 45 said screen opening intermediate the height thereof and a false bottom extending from a point intermediate of the width of said flood trough on a downward incline to said battery box immediately below said mill solution openings, an adjustable damper arranged along the upper edge of said false

bottom, means for supplying said flood trough with a regular quantity of water and means for supplying said trough with an additional supply of water.

8. A stamp mill comprising a mortar box 60 having a battery screen opening extending along one side thereof and a plurality of mill solution openings therethrough above said screen opening, a battery screen arranged in said screen opening, stamps operatively arranged in said mortar box, a flood trough secured along said mortar box on the outside thereof and having the bottom inclined downwardly and terminating along 65 said screen opening intermediate the height thereof and a false bottom extending from a point intermediate of the width of said flood trough on a downward incline to said battery box immediately below said mill solution openings, a supply pipe extending along 70 said flood trough and supplying liquid thereto between the bottom and said false bottom and a supply pipe extending along said flood trough and supplying liquid 75 thereto adjacent the solution openings in 80 said mortar box.

9. A stamp mill comprising a mortar box having a battery screen opening extending along one side thereof, and a plurality of mill solution openings therethrough above 85 said screen opening, a battery screen arranged in said screen opening, stamps operatively arranged in said mortar box, a flood trough secured along said mortar box on the outside thereof and having the bottom 90 inclined downwardly and terminating along said screen opening intermediate the height thereof and a false bottom extending from a point intermediate of the width of said flood trough on a downward incline 95 to said battery box immediately below said mill solution openings, and a tiltable reservoir trough suitably mounted along said flood trough on trunnion bearings and having a plurality of outlet openings in the bottom thereof and means for supplying said reservoir trough with liquid to tilting capacity.

Signed at Cobalt, in the District of Tun-
erkaning, the 17th day of July, 1915.

MARTIN RODERICK O'SHAUGHNESSY.
